(57) **CLAIM**

The ornamental design for the battery charger housing, as shown.

DESCRIPTION

FIG. 1 is a perspective view of a battery charger housing in accordance with the present invention.

FIG. 2 is a front view of the battery charger housing illustrated in FIG. 1.

FIG. 3 is a side view of the battery charger housing illustrated in FIG. 1.

FIG. 4 is a top view of the battery charger housing illustrated in FIG. 1; and,

FIG. 5 is a bottom view of the battery charger housing illustrated in FIG. 1.

The broken lines throughout the drawings are included for the purpose of illustrating portions of the battery charger housing form no part of the claimed design.
